UNITED STATES PATENT OFFICE.

GRANVILLE KIMBALL, OF CHICAGO, ILLINOIS.

WATER-CIRCULATING DEVICE.

SPECIFICATION forming part of Letters Patent No. 766,448, dated August 2, 1904.

Application filed November 2, 1903. Serial No. 179,589. (No model.)

To all whom it may concern:

Be it known that I, GRANVILLE KIMBALL, a citizen of the United States, and a resident of Chicago, in the county of Cook and State of Illinois, have invented certain new and useful Improvements in Water-Circulating Devices for Steam-Boilers; and I do hereby declare that the following is a full, clear, and exact description thereof, reference being had to the accompanying drawings, and to the letters of reference marked thereon, which form a part of this specification.

This invention relates to improvements in means for circulating the water in steam-boilers, and more especially to devices within the boiler by which the water delivered thereto by a feed-pump or injector operates to produce a circulation of water within the boiler.

The invention is herein shown as applied to an internally-fired "Scotch" marine boiler; but the same is equally applicable to internally-fired boilers of other types or forms of construction.

The invention consists in the matters hereinafter set forth, and more particularly pointed out in the appended claims.

In the drawings, Figure 1 is a view in central longitudinal section of a boiler embodying my invention. Fig. 2 is a cross-sectional view thereof, taken upon line 2 2 of Fig. 1.

As shown in the said drawings, A A' indicates the heads of the boiler, and A² the cylindric shell thereof.

B is a flue which extends between the heads of the boiler and contains the fire-grate C C' and a bridge-wall D. The boiler is provided at the sides and above the flue B with return-tubes E E', which lead from the combustion-chamber D' at the rear end of the boiler to an uptake E' at the forward end thereof. The heads A A' are shown as connected with each other above the tubes C by means of stay-bolts F F'.

Now referring to the particular feature constituting my invention, the same is embraced in a water-supply pipe by which the feed-water is delivered to the interior of the boiler and which extends through the upper part of the boiler or that in which the temperature is highest and terminates in a discharge end lo-

cated at the section of the boiler beneath the internal furnace-flue or fire-box, which is the coolest part of the water-space of the boiler, so that the feed-water will be heated in its passage through the feed-pipe and will be discharged after being so heated at the bottom or coolest part of the water-space of the boiler. 55

Said water-supply pipe, as shown in the accompanying drawings, embraces several parts or sections, as follows, to wit: a short section 60 G, which passes through the shell of the boiler near its forward end; a longitudinal section or part G', which extends horizontally along the side of the boiler-shell in a plane slightly above the level of the top of the return-tubes E from 65 the section G to a point near the rear end of the boiler; a horizontal transverse part G², which extends horizontally across the boiler near the rear end thereof, another longitudinal horizontal part or section G³, which extends forwardly along the opposite side of the boiler to a point near the forward end of the boiler, and a curved part or section G⁴, which extends downwardly from the forward end of the section G³ along the inner surface or shell 70 of the boiler to a point beneath the flue B and which discharges at a point between the bottom of the boiler-shell and the bottom of said flue. Said section G⁴ is preferably provided with a forwardly-extending end portion G⁵, as 75 seen in Fig. 1, which terminates near the front head A of the boiler.

To facilitate the introduction and removal of the feed-pipe described, it may be provided in its longitudinal parts G' and G³ with joints gg, 85 formed by flanges on the ends of the parts of the pipe, which flanges are joined by bolts inserted therethrough. The descending part G⁴ of the feed-pipe is also preferably jointed or made of joined sections. The drawing showing 90 the same is provided with a detachable screw-joint g', consisting of an internally-screw-threaded sleeve engaging the adjacent screw-threaded ends of the parts of the pipe, said sleeve and the ends of the pipe being oppositely screw-threaded or provided with right and left screw-threads, so that the sleeve may be applied and removed by turning the same on the said ends of the pipe. 95

It is well understood that in all internally- 100

fired boilers or those in which the furnace is located within a flue or fire-box which is within and surrounded by the external shell of the boiler the portion of the water-space of the 5 boiler least subject to the heat from the furnace and which is therefore the coolest is that at the forward end of the boiler beneath the furnace-flue or fire-box. In the operation of the device embodying my invention the 10 feed-water is delivered to this coolest part of the water-space of the boiler from the feed-pipe; but said feed-pipe is made of considerable length within the boiler and is carried for a considerable distance through the upper 15 or hottest part of the boiler before it descends to the point of discharge. As a result of this construction the entering water is heated in its circulation through the portion of the feed-pipe located in the hotter parts of the boiler, 20 so that it reaches a high temperature before it makes its exit from the end of said feed-pipe and is discharged into the water-space. It follows that by the construction described 25 a constant supply of water at high temperature is afforded to a cooler part of the water-space of the boiler beneath the furnace-flue or fire-box, and an increased circulation of water in the boiler thereby results.

The construction produces the result of causing 30 a constant circulation of water through and from the space beneath the furnace-flue or fire-box, where the water is usually "dead" or has no movement or circulation, and in the parts of the boiler above the same, with the 35 manifest advantage of making the general circulation of water in the boiler more positive and rapid, with corresponding advantage in the enhancement of steam-producing capacity.

40 I claim as my invention—

1. The combination with an internally-fired boiler having a furnace-containing flue or fire-

box located within the shell thereof, of a feed-water pipe leading from the exterior of the boiler, and provided, within the boiler, with 45 an upper part consisting of a long horizontal pipe located in the part of the boiler above said flue or fire-box, and with a descending part which leads to and discharges into the space beneath the bottom of said flue or fire-box; said pipe being closed within the boiler except at its discharge end.

2. The combination with an internally-fired boiler having a furnace-containing flue or fire-box in its lower part and return flues or tubes 55 above the same, a feed-water pipe leading from the exterior of the boiler and provided within the boiler with an upper part consisting of a long horizontal part located above the level of said return-flues, and with a descending part which leads to and discharges into the space below the bottom of said furnace-flue or fire-box, said pipe being closed within the boiler except at its discharge end.

3. The combination with a boiler having a 60 furnace-flue or fire-box and return flues or tubes, of a water-feed pipe which passes through the shell of the boiler near the front end thereof and has a horizontal part which extends backward along one side of the boiler, 70 across the boiler near its rear end and then forwardly along the other side of the boiler, and a descending part which extends downwardly from the front end of said horizontal part and terminates beneath the forward flue 75 or fire-box near the front end of the boiler.

In testimony that I claim the foregoing as my invention I affix my signature, in presence of two witnesses, this 27th day of October, A. D. 1903.

GRANVILLE KIMBALL.
